UNITED STATES PATENT OFFICE.

MILTON D. VOLLMER, OF WILLOW CITY, NORTH DAKOTA.

GAME APPARATUS.

Application filed August 10, 1927. Serial No. 212,076.

This invention relates to certain novel improvements in game apparatus and has for its principal object the provision of an improved construction of this character which will be highly efficient in use and economical in manufacture.

Among the salient objects of this invention is to provide a game apparatus which requires in the playing thereof the exercise of the skill of the player and which will afford amusement to the players and on-lookers.

Other objects will appear hereinafter.

The invention consists in the novel combination and arrangement of parts herein-after described and claimed.

The invention will be best understood by reference to the accompanying drawing showing the preferred form of construction and in which

Fig. 1 is a plan view of the game apparatus embodied in the invention;

Fig. 2 is a sectional detail view of the same taken substantially on line 2—2 of Fig. 1;

Fig. 3 is a sectional detail view, of the same, taken substantially on line 3—3 of Fig. 1; and

Fig. 4 is a sectional detail view, of the same, taken substantially on line 4—4 of Fig. 1.

Referring more particularly to the drawing, 10 indicates a baseboard and extending around the peripheral edges of this baseboard are upstanding flanges 11 and 12.

Mounted centrally upon this base board is a bearing head 13 having its upper edge portion bifurcated to rockably receive a web 14 which integrally joins two guideways 15 together. These guideways are substantially channel shaped in cross section having their outer end portions 16 closed and their adjacent end portions 17 opened. Adapted for movement longitudinally, in a manner hereinafter set forth, in these guide ways is a ball or pellet 18.

Formed in the baseboard and extending substantially at right angles with respect to the guideways are two parallel extending plates 19 forming a dove-tailed groove 20 which open laterally into slots 21 formed in the base plate. Platforms are indicated at 22 and these platforms have formed on their under sides dove-tailed flanges 23 which slidably set in the groove 20 and mounted on these platforms to provide

finger pieces are animate objects 24 shown in the present instance as goats. Engaging the edge 25 of each of the platforms and extending inwardly beneath the baseboard 60 and working in the slots is a bar 26. This bar 26 has its inner end portion 27 rolled to provide a loop and secured to this loop is one end portion of a rubber band 28 the opposite end portion of the band being secured inwardly of the loop to the baseboard through the medium of a tack 29.

Secured to the loop 27 is one end portion 30 of a drawing cord 31. The opposite end portion of this drawing cord extends beneath the baseboard and passes upwardly through an opening 32 for connection as at 33 to its corresponding guideway 15. The guide ways and their web portions are pivotally connected to the head 13 through the 75 medium of a pintle 34.

The opposite correspondingly end portions 35 of the baseboard is divided into a plurality of compartments or spaces 36 of various dimensions with respect to widths. 80 The flanges 11 have formed therein a plurality of spaced aligned opening 37 into which is adapted to be removably positioned an indicating pin. (Not shown).

Operation.

In use, the pellet or ball is positioned in the channel of the guide way opposite the guide way to which the drawing cord to be drawn is attached. One of the players 90 grasps the object 24 to which that drawing cord is attached between the fingers. By sliding the platform 25 carrying this object outwardly this drawing cord will be brought taut and rock the guideways so as 95 to position the guide way to which this cord is attached in its lowermost position and raise the opposite guide way in its uppermost position. The tilting of the guide ways will cause the ball to roll downwardly 100 toward the open space between the inner adjacent ends of the guideway. The object is to release the animate object 24 at the time when the ball reaches this open space. When the object 24 is moved outwardly the 105 rubber band will become taut and upon release of the object 24 this platform the band will snap the same in an inner direction for contact with the ball. Should the object 24 strike the ball, the ball according to its direction of impact with the object 24 will be thrown into one of the spaces 36. As these

spaces are of various widths it is intended that they indicate a numerical score such as for example the largest of the spaces if indicating 5 and the ball finds lodgment in 5 this space the operator will set the pin in the fifth hole of the spaced holes in either of the flanges 11.

From the above description taken in connection with the accompanying drawing it 10 will be manifest that the game is of such structure as will afford unbounded amusement to the players and onlookers.

While I have illustrated and described the preferred form of construction for carrying 15 my invention into effect this is capable of variation and modification without departing from the spirit of the invention. I, therefore, do not wish to be limited to the precise details shown but desire to avail myself of such variation and modification as comes within the scope of the appended 20 claims.

Having thus described my invention what 25 I claim as new and useful and desire to secure by Letters Patent is:

1. In a game apparatus, a teeter structure 30 providing two opposite aligned guide ways having adjacent end portions opened to provide a transverse passage, a ball movable in the guide ways toward said opening, means 35 yieldably urged in a direction substantially at right angles with respect to said teeter structure toward said opening for striking engagement with said ball to throw said ball from movement in said guide ways when 40 said ball reaches said opening, and means operable by said ball striking means for imparting see-saw action to said teeter structure to cause said ball to gravitate toward said opening.

2. In a game apparatus, a base board, a teeter structure mounted on said base board and providing two opposite aligned guide ways having adjacent end portions spaced 45 to provide a transverse opening, means movable toward said opening, means providing connection between said movable means and said teeter structure to impart tilting movement to said structure, and a ball movable in the guide ways and movable by gravity upon tilting of said teeter structure toward said opening and adapted to be struck by said movable means and thrown from said guide ways through said openings.

3. In a game apparatus, a base board, a teeter structure mounted on said base board

and providing two opposite aligned guide ways having adjacent end portions spaced to provide a transverse opening, means movable toward said opening, means providing 60 connection between said movable means and said teeter structure to impart tilting movement to said structure, and a ball movable in the guide ways and movable by gravity upon tilting of said teeter structure toward said 65 opening and adapted to be struck by said movable means and thrown from said guide ways through said openings and said base board providing a plurality of spaces varying in width and into which said ball is adapted 70 to be projected by said movable means.

4. In a game apparatus, a base board, a teeter structure mounted upon the base board and providing two aligned guide ways, a platform having slidable connection with the base board and elastic member having one end portion secured to said base board, means connecting the opposite end portions of said member to said platform for urging said platform in a direction toward said teeter structure, an animate object mounted on said platform away from said teeter structure whereby said guide ways will be tilted in one direction, and a ball adapted for movement by gravity within said guide ways when the direction of tilting movement of said guide ways is changed, said ball being adapted to be struck by said object and projected away from said teeter structure.

5. In a game apparatus, a base board, a teeter structure mounted upon the base board and providing two aligned guide ways, a platform having slidable connection with the base board and elastic member having one end portion secured to said base board, means connecting the opposite end portions of said member to said platform for urging said platform in a direction toward said teeter structure, an animate object mounted on said platform away from said teeter structure whereby said guide ways will be tilted in one direction, and a ball adapted for movement by gravity within said guide ways when the direction of tilting movement of said guide ways is changed, said ball being adapted to be struck by said object and projected away from said teeter structure and said base board providing a plurality of divided spaces into which said ball is adapted to be selectively projected by said object.

In testimony whereof I affix my signature.
MILTON D. VOILLMER.
